UNITED STATES PATENT OFFICE.

RICHD. D. MOTT, OF SPRING GARDEN, PENNSYLVANIA.

STEREOTYPE-PAN.

Specification of Letters Patent No. 10,704, dated March 28, 1854.

To all whom it may concern:

Be it known that I, RICHARD DIXON MOTT, of Spring Garden, in the county of Philadelphia and State of Pennsylvania, have invented a new and useful Improvement on 5 Stereotype-Pans; and I do hereby declare that the following is a full, clear, and exact description of the construction and operation of the same, reference being had to the 10 annexed drawings, making a part of this specification, in which—

Figure 1, is a perspective view, showing the three several parts of the pan separated. Fig. 2, is a side view of the same, having the 15 front part of the pan removed, in order to show the interior, and Fig. 3, is a plan view of the upper side of the casting plate, having one of the cross projections, grooves, or attachments, removed, in order to show the 20 recessed corners of the plate.

The same letters and figures, refer to like parts when in the different drawings.

This improvement is designed for casting metallic stereotype plates, of uniform 25 thickness, with plaster of Paris molds, in horizontal pans, and consists of an iron box or pan (A) and lid (B) constructed of the usual shape and size, and a casting plate (C) (instead of a "floater") upon both 30 sides of which any required number of beveled projections, grooves, or attachments (D, D, D,) are constructed, forming receptacles for the plaster molds (E, E, E) and by means of which attachments or grooves, 35 the said plaster of Paris molds are retained close up to, and with their faces parallel with the surfaces of the casting plate, as shown in Fig. 2. The said beveled attachments or grooves being so constructed at 40 their ends as to present beveled or chisel-like cutting edges (1, 1, 1, 1) or their equivalents which cut from the edges of the sides of the plaster of Paris molds (whatever of excess the said molds may have in width 45 greater than the spaces between any two of the said attachments or grooves) when the plaster molds are forced into their proper positions between them and against the faces of the casting plate, as shown in Fig. 2. By 50 having cutting edges attached to the plate I obviate the objection arising from the unequal shrinking of the molds in drying or baking and the consequent difficulty of trimming them to fit the receptacles before baking. At each end of these attachments or 55 grooves (D, D, D) a small recess or chan-

nel, or its equivalent (2, 2, 2) is made, next to the plate, of a sufficient size to allow the melted stereotype metal to flow freely to the plaster molds, which it enters through the small notches (3, 3, 3) cut on each end of the molds across the raised edges next to the casting plate—the pressure arising from the density of the melted stereotype metal, when the pan is sunk in the kettle, being sufficient to force the said metal into the smallest cavities. The four corners of this casting plate (C) as also the four corners of the lid (B,) have their extreme points cut away sufficiently, as shown at 4, 4, to allow the 60 melted metal to enter the pan and also the 65 under side of the casting plate.

The attachments or grooved projections (D, D, D,) may be secured permanently to the plate (C) or they may be made adjustable—when adjustable they may be securely fastened to the plate by means of screws—these being made several properly adapted sets of screw holes in the plate, so that the attachments may be shifted and secured at pleasure, to suit various sizes of 70 molds the unoccupied holes in the plates being filled with flush screws adapted thereto. The pan, its lid, and casting plate with its attachments, are intended to be constructed 75 of iron. At each end of the casting plate, on the two end attachments or grooved projections, a small iron pin is inserted across the middle of a groove or depression therein (as shown at 5,) for the purpose of furnishing a hold at each end of the plate for lifting it in before casting.

Having thus described and illustrated my improvement in the stereotype pan, I will proceed to describe the mode of operation.

After the plaster molds from which the stereotype plates are to be made are properly baked in the usual manner and degree, they are severally pressed each within a pair of the projections, or grooved attachments by 80 the operator holding the plate and mold and sliding the said mold with its face up against the face of the said plate, while the cutting edges shave the molds until they have passed to their proper positions therein as shown in 85 Fig. 2. The casting plate is then placed in the pan and the lid placed upon it, (thus securing the casting-plate between the lid and bottom of the pan) as shown in the 90 same figure. The usual clamp and screw 95 is now put on to secure the whole together, and it is ready for sinking into the melted 100 105 110

metal, which part of the process being understood by all stereotypers, it is unnecessary here to describe.

The advantages of this improved mode of 5 constructing stereotype pans over the one now in use, having what is technically called a "floater" instead of the casting plate herein described, are—First, the plates can be cast of a uniform thickness, and so near the 10 required standard as to save at the lowest computation, seventy-five per cent. in shaving down the plates during the process of finishing; second, two casts can be made at one immersion of the pan; third, the greater 15 ease and facility with which the stereotype plates can be removed from the casting plate when the cast is cooled; fourth, the trouble and expense of "backing up" thin plates (very often necessary in the plan now 20 in use) may be avoided, and, sixth, the casting plates are less liable to be broken than the "floaters" now in use, as very little force or hammering will be necessary to remove the stereotype plates after the cast is made. 25

The peculiarity of this improvement on stereotype pans, consists in the substitution and use of the casting plate (C) with its adjustable beveled attachments (D D D) having chisel-like cutting edges (1, 1, 1, 1,) 30 on their ends for cutting and trimming the single faced plaster molds as they are forced between them—one plate only being used, but having both its sides fitted with the cut-

ting-edged attachments, and the plate held down near the middle height of the pan in a 35 horizontal position, during the process of casting, thus securing a full and perfect face and an even and regular back to each stereotype plate; and whereby also greater facility is afforded both in casting and removing the 40 stereotypes after the cast becomes cool.

Having thus fully described the nature of my invention, and the mode of operation, and pointed out some of its advantages, I 45 proceed to state that I do not claim the pan proper, nor its lid, as these are common; but

What I claim as my invention and desire to secure by Letters Patent is—

The substitution and use in stereotype pans of a single horizontal casting plate (C) 50 combined with the adjustable attachments (D D D D) for holding the single faced plaster molds; the said attachments having chisel-like cutting edges (1, 1, 1, 1,) on their ends, for cutting and trimming the said 55 molds as they are forced by the operator between them and the plate and the said casting plate having both its sides fitted with the cutting-edged attachments; all constructed substantially and for the purposes 60 as herein described and illustrated.

RICHARD DIXON MOTT.
